UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

MACHINE-SWITCHING TELEPHONE-EXCHANGE SYSTEM.

1,203,887.

Specification of Letters Patent.

Patented Nov. 7, 1916.

Application filed September 27, 1915. Serial No. 52,880.

To all whom it may concern:

Be it known that I, ALBEN E. LUNDELL, a citizen of the United States, residing at New York, in the county of Bronx and State 5 of New York, have invented certain new and useful Improvements in Machine-Switching Telephone-Exchange Systems, of which the following is a full, clear, concise, and exact description.

This invention relates to telephone exchange systems employing machine switching.

It is the practice to signal a wanted party by intermittently ringing the bell at his sub- 15 station. This is done automatically by a ringing machine at the connector, such machine having a commutator on the shaft or equivalent means for breaking the call up into short rings. It frequently happens 20 that connection is made with a wanted line during what is known as a silent interval of the ringing machine; that is, while the open circuit part of the commutator is connected with the called party's line. This re- 25 sults in loss of time.

The object of this invention is to provide a circuit arrangement whereby ringing current is applied to the called line for a short interval immediately the connector is set 30 thereon, and intermittently to apply current thereto if the called subscriber does not respond to such preliminary signal.

In accordance with this invention two sources of ringing current are provided, one 35 being the ordinary ringing machine adapted to ring intermittently the called party's bell, and the other a continuous source of ringing current. The application of these sources of current to the called line is con- 40 trolled by a relay. This relay is adapted to be connected in circuit with an interrupter. If, when the connector is set upon the called line, said interrupter is on an insulated segment of the commutator, this relay will at 45 its back contact instantly apply ringing current from said source of continuous ringing current to the called line. If, on the other hand, the interrupter brush is on a metallic segment, the relay will at its ar- 50 mature and front contact apply current to the called line from said ringing machine. The ringing machine and interrupter are so related that the ringing interval of the former begins before the interrupter brush 55 passes onto a metallic segment of the com-

mutator. Thus if, when the connector reaches the called line terminals, the said relay is energized, ringing current is instantly applied to such line from the ringing machine. This relay, when energized, 60 locks up in a circuit independent of the interrupter and maintains the ringing machine connected to the called line in circuit with a marginal relay. The called party's bell is thus intermittently rung un- 65 til he answers, when the marginal relay opens the ringing circuit.

The invention will be more readily understood when described with reference to the accompanying drawing, which illustrates only so much of a telephone exchange system as is necessary for a comprehension of the invention.

The calling substation A may be extended to a first selector, the brushes 10, 11 and 12 and terminals 13, 14 and 15 only of which are shown, by a line finder or equivalent means upon the removal of the receiver thereat. This selector may be of the power-driven type and may be set upon the terminals 13, 14, 15 of an idle trunk 16, 17, 59, by any well-known means, as shown, for example, in British Patent No. 21,260 of 1911. The springs 18, 19 designate sequence switch contacts of the first selector sequence switch, which contacts, during the control of the selectors and connector are closed to their bottom contacts to associate the operator's sending equipments with such switches. During the setting operation of 90 the connector, the sequence switch spring 26 would be closed to its bottom contact to associate the sender with such connector.

When the train of switches has established the connection to the desired line, the springs referred to would be closed to their top contacts to disconnect the sender and complete the talking circuit. When the connector brushes 20, 21, 22 are set upon the terminals 23, 24, 25 of the selected line, a control relay (not shown) becomes deenergized. This relay closes its back contact and advances the sequence switch of the connector to the next position, transferring its spring 26 to its upper contact. In such 105 position, the sequence switch spring 27 is closed, resulting in the energization of relay 28 over the following circuit: free pole of battery, sequence switch spring 27, conductor 30, relay 28, conductor 31, armature and 110

back contact of relay 29, conductor 32, armature and back contact of relay 33 to ground. Relay 28 transfers its armatures to their inner contacts. This results in the closure 5 of the following circuit to ring bell *b* at substation B: generator 34, left armature and back contact 57 of relay 35, conductor 36, relay 33, conductor 37, armature 50 and front contact of relay 28, connector sequence 10 switch contact 38 (now closed), brush 21, terminal 24, conductor 39, bell *b*, condenser *c*, conductor 40, terminal 23, brush 20, sequence switch contact 41 (now closed), armature 51 of relay 28 and its front contact 15 to ground. The source of ringing current 34 is continuously closed to the back contact 57 of the left armature of relay 35, and consequently when relay 28 becomes energized as the connector reaches the called 20 line, the bell *b* is instantly rung. An interval of say ten seconds may now elapse before brush 42 of interrupter 43 rides onto a metallic segment 44 of such interrupter. If the subscriber at substation B removes his 25 receiver 52 from its switchhook during this interval, the increase in the strength of the ringing current, due to the closure of the shunt about the bell *b* and condenser *c* including the transmitter 53 and primary 54 30 of the induction coil, causes the relay 33, which is marginal, to become energized in the well-known manner. This relay in attracting its armature opens a shunt about relay 29, which in energizing in turn shunts 35 out relay 28. Relay 28 in retracting its armatures 51, 50, opens the ringing circuit just traced and extends link conductors 55 and 56 to the brushes 20 and 21 of the connector over sequence switch contacts 41 and 40. If the called party does not respond 40 during this interval, when the brush 42 of interrupter 43 next engages a metallic segment 44 of the commutator, the following circuit is closed to energize relay 35: 45 free pole of battery, metallic segment 44, brush 42, conductor 45, spring 46 of relay 35 and its back contact, relay 35, conductor 47, armature 48 of relay 28 and its front contact to ground. Relay 35 by attracting its 50 right armature, locks itself to ground at the armature 48 and front contact of relay 28 independent of the interrupter 43. By attracting its left armature, it opens the ringing circuit just traced from the generator 55 34 and closes the following ringing circuit from generator 49: free pole of battery, generator 49, interrupter 60, left armature and front contact 58 of relay 35, conductor 36, relay 33, armature 50 and front contact of 60 relay 28, sequence switch contact 38, brush 21, terminal 24, conductor 39, bell *b*, condenser *c*, conductor 40, terminal 23, brush 20, sequence switch contact 41, armature 51 and front contact of relay 28 to ground. 65 The bell *b* at substation B will now be in-

termittently rung from the ringing machine 49, 60; and when the called party answers, the marginal relay 33 operates to cut off the ringing current, as described.

The interrupters 43 and 60 are so related 70 to each other that if, when the connector is set upon the called line, the brush 42 of interrupter 43 is in contact with the metallic segment 44 of the commutator, the brush 61 of interrupter 60 is also riding over a 75 metallic segment 62 of such interrupter, in order that current may be immediately applied to the called line.

In order to permit trip relay 33 to cut off 80 the ringing current during the silent interval of the ringing machine, tripping battery may be connected to a metal segment on the shaft of interrupter 60 in a manner well known in the art.

Talking current is fed to the calling party 85 from battery 63 and to the called party from battery 64 in the well-known manner.

The release of the switches may take place 90 by the depression of a key by the operator, as shown in detail in the patent mentioned.

What is claimed is:

1. In a telephone exchange system, the combination with telephone lines, a connector wherein said lines terminate, and means for setting said connector on said lines, of a 95 relay, a source of current and an interrupter for operating the same, two sources of ringing current controlled by said relay, electromagnetic means adapted to operate when the connector is set on the called line and to 100 connect one or the other source in circuit with the called line dependent upon the condition of said relay, and means for cutting off the ringing current when the called party answers.

2. In a telephone exchange system, the combination with telephone lines, a connector wherein said lines terminate, means for setting said connector on said lines, a relay, a source of current and an interrupter for 110 operating the same, a source of continuous ringing current connected to the back contact of said relay, a source of interrupted ringing current connected to the front contact of said relay, electromagnetic means 115 adapted to operate when said connector is set on the called line to connect one or the other of said ringing current sources to the called line dependent upon the condition of said relay, and means for cutting off the ringing current when the called party answers.

3. In a telephone exchange system, the combination with telephone lines, a connector wherein said lines terminate, and means for setting said connector on said lines, a 125 relay, a source of continuous ringing current connected to the back contact of said relay, a source of interrupted ringing current connected to the front contact of said relay, a source of current and an interrupter 130

adapted to operate said relay, said inter-
rupter being adapted to operate said relay
only when said source of ringing current is
closed to the front contact of said relay, elec-
5 tromagnetic means adapted to operate when
said connector is set on the called line to con-
nect the armature of said relay and the ring-
ing current source at that moment connected

thereto to the called line, and means for cut-
ting off the ringing current when the called 10
party answers.

In witness whereof, I hereunto subscribe
my name this 25th day of September, A. D.
1915.

ALBEN E. LUNDELL.
